SAND WEDGE GOLF CLUB HEAD

Lester Z. Brown, Jr., 4816 Glencairn Road,
Los Angeles, Calif. 90027

Filed Oct. 9, 1967, Ser. No. 8,929

Term of patent 14 years

(Cl. D34—5)

FIGURE 1 is a perspective view of a sand wedge showing my new design;

FIGURE 2 is a view taken in the direction of arrow 2 as indicated in FIGURE 1;

FIGURE 3 is a view in elevation taken in the direction of arrow 3 indicated in FIGURE 1;

FIGURE 4 is a view taken in the direction of arrow 4 as indicated in FIGURE 1;

FIGURE 5 is an end view from the toe end of the club as indicated by the arrow 5 in FIGURE 1;

FIGURE 6 is a view in elevation taken in the direction of arrow 6 as indicated in FIGURE 1; and

FIGURE 7 is an end view of the club viewing the same from the heel of the club to the toe of the club as indicated by arrow 7 in FIGURE 1.

The upper portion of the hosel is conventional and is therefore shown in broken lines with a fragmentary

broken line showing of a conventional shaft seen in FIGURE 1 for illustrative purposes.

I claim:

The ornamental design for a sand wedge golf club head, as shown and described.
